CLAIM

The ornamental design for a touch screen display device, as shown and described.

DESCRIPTION

FIG. 1 is a perspective front view showing our new design for the touch screen display device.

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear view thereof;

FIG. 8 is a front perspective front view showing an alternate embodiment of our new design for the touch screen display device, similar to that shown in FIGS. 1-7, but of a larger proportional size;

FIG. 9 is a front view thereof;

FIG. 10 is a right side view thereof;

FIG. 11 is a left side view thereof;

FIG. 12 is a top view thereof;

FIG. 13 is a bottom view thereof; and,

FIG. 14 is a perspective rear view thereof.

Broken lines immediately adjacent shaded areas represent bounds of the claimed design. All other broken lines are directed to unclaimed features. The broken lines form no part of the claimed design.
